[57] **ABSTRACT**

This disclosure relates to a frictional gripping type of railroad car retarder having a plurality of vibrational dampening wheel and tire assemblies disposed at selected intervals along the running rails in the car retarder for engaging the flanges of the wheels of the passing railway vehicles thereby dissipating vibrational energy imparted to the wheels via the slip-slide action of the brake shoes to thereby prevent the production of wheel squealing or screeching noises.

**VIBRATIONAL DAMPENING ARRANGEMENT
FOR RAILROAD CAR RETARDERS**

SUBJECT OF THE INVENTION

This invention relates to a novel noise suppression arrangement for railway braking apparatus and more particularly to a unique rubber dampening arrangement for removing vibrational energy from the wheels of a railway vehicle for preventing wheel screeching sounds from being produced by wheel clamping types of railroad car retarders.

BACKGROUND OF THE INVENTION

In a gravity type of railroad marshalling or classification yard, it is conventional practice to employ gripping or clamping types of car retarders at both master and group locations to control the leaving speeds of humped railway cars or vehicles. Additionally, it is also becoming increasingly common to employ a car retarder at the exit end of each of the class tracks in the yard to stop the oncoming railway cars as they are processed into the respective classification tracks. The car retarders frictionally engage or grip the opposite sides of the car wheels to slow down the moving railway cars as they pass through the master and group location and to stop the railway vehicles in the class tracks. On numerous occasions, the frictional gripping action between the brake shoes and wheels results in extremely loud and piercing squealing noises to permeate the immediate surrounding area bordering the yard. The bordering area may include residential, business, industrial, commercial and/or governmental properties and may consist of homes, apartments, offices, factories, schools, hospitals and the like. These high pitched screeching sounds not only are irritating or annoying to residents of the area but also are painful and injurious to working personnel in the yard. In some cases, a partial or total loss of hearing may result when employees are exposed to the retarder noises for extended periods of time. It has been found that longtime exposure to sounds above a given critical level adversely affect workmen or supervisory personnel who work in the area of the car retarders. These acute and detrimental sound waves are produced by the stick-slip or rubbing action which takes place between the sides of the wheel rims of the moving car and the engaging surfaces of the brake shoes of the actuated car retarder. In actual operation, it has been found that the most troublesome pitch or frequency range of the retarder generated sound waves lies between 2,000 to 4,000 hertz. Further, the loudness or amplitude level of the noises may reach a 130 decibels db(A) or more at a distance of 8 feet or less from the car retarder. Otolaryngologists, audiologists and other qualified specialists have found that human beings experience discomfort and pain when exposed to noise levels of 120 db(A) or more and that repeated exposure to such high levels of noise can eventually result in hearing losses. Recently there have been numerous proposals and attempts to eliminate or at least reduce the noise level in order to comply with the regulations of the Occupational Safety and Hazard Act and the noise pollution ordinances of the given locale. However, each of these previous attempts was either prohibitively expensive or mechanically unsound and, therefore, did not meet with industry-wide acceptance. The proposition of replacing steel brake shoes with ductile iron appeared plausible but proved uneconomical since ductile iron shoes wear four times as fast as steel. Hence, a railroad car retarder equipped with ductile iron shoes normally requires four times as many shoe replacements as an all steel retarder. Obviously, a car retarder fitted with ductile iron shoes needs a greater number of adjustments and requires more periods of maintenance than a car retarder equipped with steel shoes. The use of lubricants, such as, oils and mixtures of other unctuous liquids, that are sprayed or otherwise applied to the contacting surfaces of the brake shoes and wheels for eliminating wheel squealing or screeching noises is also possessed of several shortcomings. The utilization of lubricants not only materially decreases the effective braking length of the car retarder but also dramatically increases the initial purchase price as well as the subsequent maintenance cost of the overall car retarder. A further deleterious effect of employing lubricants in combating the noise pollution problem is the unctuous ground covering in the immediate area of the car retarder as well as the oil dropping pollution caused throughout the classification yard. A further method in attempting to resolve the noise pollution problem in classification yards has been the erection of sound barriers or walls on the respective sides of the railroad car retarder. In previous types of noise barriers, the use of porous noise absorption material was unacceptable in that they soon become relatively ineffective in suppressing the noise produced by the car retarder. The principal reason for the loss in sound attenuation resides in the fact that the porous material readily becomes clogged with foreign matter, such as, dirt, oil, grease, water, ice and the like, which is common in a classification yard environment. In addition, low density types of noise absorption materials are generally susceptible to rapid deterioration due to the adverse physical and climatic conditions which are present in railroad yard milieu. Further, it will be appreciated that the maximum theoretical value of noise reduction or attenuation provided by a barrier structure is approximately 25 db which in many cases is insufficient to conform with the noise abatement ordinances in the particular locale and the safety standards set forth in the Occupational Safety Hazard Act of 1970. In present classification yards and in future proposed yard locations, it has been found that even at substantial distances, 5,000 feet or more, the noise level that permeates the area beyond the boundary line of the yard is in excess of the maximum permissible amplitude set forth in many of the local noise abatement ordinances. Thus, there is a vital need for providing an efficient noise reduction arrangement for effectively reducing or eliminating wheel squealing or screeching sounds produced by railroad car retarders. In addition, there is a requirement for attenuating screeching noises that are produced by the wheels when a vehicle traverses a curve, tight gauge or the like in the trackway.

nomical since ductile iron shoes wear four times as fast as steel. In present classification yards and in future proposed yard locations, it has been found that even at substantial distances, 5,000 feet or more, the noise level that permeates the area beyond the boundary line of the yard is in excess of the maximum permissible amplitude set forth in many of the local noise abatement ordinances. Thus, there is a vital need for providing an efficient noise reduction arrangement for effectively reducing or eliminating wheel squealing or screeching sounds produced by railroad car retarders. In addition, there is a requirement for attenuating screeching noises that are produced by the wheels when a vehicle traverses a curve, tight gauge or the like in the trackway.

OBJECTS AND SUMMARY OF THE INVENTION

Accordingly, it is an object of this invention to provide a new and improved vibrational energy absorbing rotary device arrangement for frictional clamping types of railroad car retarders.

Another object of this invention is to provide a unique noise reduction arrangement for railway braking apparatus by disposing a series of rubber tires along the running rail for dissipating sound producing energy imparted to the wheels of railway vehicles.

A further object of this invention is to provide a unique vibrational dampening arrangement employing a plurality of elastomeric rotary devices for contacting the wheels of railway vehicles as they pass over a curved railroad track.

Yet another object of this invention is to provide a novel noise suppressing arrangement utilizing a series of vibration absorbing roller devices disposed along the length of a car retarder.

Yet a further object of this invention is to provide an antinoise arrangement for railroad cars employing a rotary wheel and tire assembly for removing vibrational energy from the wheels of passing railway vehicles.

Still another object of this invention is to provide a series of rubber tires which are rotatably supported at selected points along the length of a railway car retarder to dampen the sound producing vibrations imparted to the wheels of traversing railway cars.

Still a further object of this invention is to provide in combination a section of railway trackway for guiding and supporting the wheels of passing railway vehicles, characterized by a plurality of vibrational energy absorbing rotary devices disposed at selected points along the section of railway trackway and securely fastened to the trackway for contacting the vehicle wheels for removing vibrational energy from the wheels for preventing the production of wheel squealing noises.

An additional object of this invention is to provide in combination a railroad car retarder having a plurality of operating units disposed along the length of a running rail of a trackway, an elongated braking bar disposed on each side of the running rail and carried by the plurality of operating units, the elongated braking bar including a brake beam and a brake shoe for engaging the wheels of railway vehicles, characterized by a plurality of vibration absorbing rotary devices disposed at selected points along the running rail for contacting the vehicle wheels for removing vibrational energy from the wheels for preventing the production of wheel screeching sounds.

Yet an additional object of this invention is to provide a novel rubber tire vibration dampening arrangement for railway cars which is economical in cost, simple in construction, easy to install and reliable in operation.

In the attainment of the foregoing objects, there is provided a gripping type of railroad car retarder having a plurality of operating units located along the length of the running rail of a section of track in a classification yard. Each of the operating units includes a fluid pressure motor and a pair of pivotal levers. Each of the pivotal levers carries an elongated braking bar which includes a brake beam and brake shoe movable to a braking position for engaging the sides of the wheels of railway vehicles traversing the car retarder. The running rail which extends substantially along the length of the car retarder or which may be a section of curved trackway or tight gauge is provided with a plurality of vibration absorbing rotary devices located at selected points along its length. Each of the vibration absorbing rotary devices includes a wheel and rubber tire assembly. The assembly is rotatably carried by an axle member which is secured to one of a plurality of positions in the web portion of the running rail. Thus, the rubber tires engage the flanges of the passing wheels of the vehicles and remove vibrational energy imparted to the wheels by the slip-slide action of the brake shoes so as

to prevent the development of wheel squealing or screeching noises.

Other objects, features and advantages of this invention will become more apparent from the following description of the preferred embodiments described with reference to the accompanying drawings forming a part of this specification, in which:

FIG. 1 is a fragmentary top plan view of a track section in, for example, a hump type of railroad freight car classification yard, utilizing a squeeze or gripping type of car retarder for controlling the speeds of moving railway vehicles and including a plurality of vibration absorbing rotary devices selectively located along the length of the running rail for reducing the production of wheel squealing noises.

FIG. 2 is an enlarged sectional view taken along the lines II-II of FIG. 1.

FIG. 3 is a greatly enlarged fragmentary prospective view, partly in section, of one of the vibrational absorbing rotary devices utilized in the railway braking apparatus of FIG. 1.

Referring now to the drawings and in particular to FIGS. 1 and 2 there is shown a railroad car retarder generally characterized by numeral 1. In hump or gravity types of classification yards, it is desirable to sort and classify the freight cars or vehicles of an incoming train into other trains in accordance with their contents and/or their next destination. The railway cars of the incoming trains are pushed over a hump or incline so that the force of gravity moves the cars to the appropriate location in the selected class track. However, various parameters, such as, car weight, rolling resistance, wind velocity and the like, cause each of the free rolling cars to travel down the trackway at a different speed. In order to control the speed of the moving cars in accordance with their rollability and the distance-to-go, it is common practice to provide suitable braking apparatus at the hump and group track locations in the classification yard. Generally, the braking apparatus takes the form of the squeeze or gripping type of car retarder which has braking bars that are movable into and out of engagement with the wheels of passing railway cars for controlling the speed thereof. In group and hump applications, it is common practice to employ a dual track car retarder in order to ensure that sufficient braking effort is exerted on the wheels of the cars as they pass through the retarder.

As shown in FIG. 1, the dual track car retarder 1 includes a plurality of suitable operating units OU appropriately disposed along each rail of a section of trackway. Each of the operating units OU is substantially identical, and accordingly, a description of one will suffice for all of the operating units. As best shown in FIG. 2, a typical operating unit OU consists of an upper lever 3 and a lower lever 4. The levers 3 and 4 are operated by a fluid actuated motor M which causes pivotal movement about the common fulcrum point or pin 5. It will be seen that the free end of the upper pivotal lever 3 is also pivotally connected to the pneumatic cylinder member 6 of motor M while the free end of the lower pivotal lever 4 is also pivotally connected to the reciprocal piston member 7 of motor M. It will be noted that the upper lever 3 carries an elongated outer braking bar 8 while the lower lever 4 carries an elongated inner braking bar 9. As shown in FIG. 1, the braking bars 8 and 9 extend parallel to the track rails and are adapted to be moved relative to the track rails

into braking and nonbraking positions. The braking bars 8 include brake beams 10 which are bolted to the upper surface of levers 3 while the braking bars 9 include brake beams 11 which are bolted to the upper surface of levers 4. The braking bars 8 include the elongated outer replaceable brake shoes 12 which are bolted to the brake beams 10, and the braking bars 9 include the elongated inner replaceable brake shoes 13 which are bolted to the brake beams 9. Thus, the pivotal movement of the levers 3 and 4 about the common fulcrum point causes the braking bars 8 and 9 to move toward and away from each other as the fluid motors M are energized and deenergized via conduits 14 and 15 which are connected to a suitable source of fluid pressure (not shown). Hence, upon application of fluid pressure via conduits 14 and 15 to fluid actuating motors M, the braking bars 8 and 9 undergo an elevating and closing movement so that the brake shoes 12 and 13 frictionally engage the sides of wheel W of a traversing railway vehicle, as shown in FIG. 2. Conversely, upon the venting of the air from the actuating motors M to atmosphere via conduits 14 and 15, the force of gravity with the assistance of return springs S operating on levers 3 and 4 acts to lower and open the braking bars 8 and 9 to their normal nonbraking position. Accordingly, when a railway car or cut of cars moves through the retarder, the closing and opening of the braking bars allows for the speed of the traversing car or cars to be controlled in accordance with its ultimate destination in a class track.

A common occurrence in conventional squeeze or grip types of railroad car retarders is the production or development of large amplitude vibrations in the vehicle wheels and braking bars when the retarder remains closed for a given period of time. These vibrations imparted to the wheels build up and result in a very loud and high pitched squealing or screeching noise to be produced by the retarder. That is, the stick-slip mechanism or the rubbing-grating action which takes place between the surfaces of the brake shoes and the sides of the vehicle wheels produces sufficient sound generating energy over a period of time to cause wheel squeal. Thus, the sound producing energy should be prevented from building up to the point where the retarder is capable of developing wheel screeching sounds. In order to abate this noise problem, it has been found to be desirous and advantageous to reduce or dampen out the sound producing energy by employing a vibration absorbing arrangement in combination with the railroad car retarder. The noise reduction or elimination is accomplished by constructing the running rail within the confines of the retarder of an appropriate sound absorbing material. It will be appreciated that the entrance rail sections 20 and 21, namely, the left-hand rails as viewed in FIG. 1 of the drawings, are standard steel rails, such as, 90 lb. rails. As shown, the rails 20 and 21 are fastened to the ends of running rails 22 and 23, respectively, in the usual manner by means of rail joints 24 and 25. The running rails 22 and 23 extend substantially the length of the car retarder 1, and the ends are in abutting relationship with the ends of exit rails 26 and 27. As is conventional, the running rails 22 and 23 are securely fastened to exit rails 26 and 27, respectively, by means of rail joints 28 and 29.

As previously mentioned, if the car retarder remains closed for a given period of time when a railway vehicle is moving through it, the brake shoes will cause the

wheels to begin to vibrate due to the slip-slide braking action. In previous retarder operations, this impetuous force or imparted vibrational energy of the wheels resulted in the generation of very high pitched squealing or screeching noises. In the present instance, the wheel squealing noises are circumvented by employing a vibrational energy dampening or absorbing arrangement in combination with the car retarders. As shown, the novel noise suppressing arrangement includes a plurality of a series of vibration absorbing rotary devices 30 suitably located at selected points along the length of both of the running rails 22 and 23. In viewing FIGS. 2 and 3, it will be observed that each of the rotary devices 30 includes a wheel and tire assembly rotatably mounted on an axle or shaft 31. The wheel and tire assembly includes an outer solid, semipneumatic or pneumatic rubber tire 32 and inner metallic rim or mounting wheel 33. The rim 33 is journaled to the outer end of the pivotal shaft 31 which is located on the inner sides of the running rails 22 and 23. The free end of the axle is slightly reduced and passes through a selected one of a plurality of contiguous holes or apertures 34a, 34b or 34c located in the web portion of the running rails. As shown in FIG. 3, the reduced portion is threaded and is located in the center aperture 34b so that the assembly may be vertically adjustable or raised when the tread of the tire 32 becomes worn after a period of usage. Normally, a new or replacement wheel and tire assembly is located in the lowest slot 34c and is raised 20 in steps from slot 34c to slot 34b and, in turn, from slot 34b to slot 34a as tire wear occurs. It will be seen that the shoulder portion 35 is drawn against the inner side of the web portion of rail 20 by a nut 36 and washer 37 which fit onto the threads of the reduced portion and 25 which hold the entire assembly in secure relationship to the top of the rail head. It will be appreciated that as the humped vehicle enters the car retarder, the slip-slide action between the wheels W and brake shoes 10 and 11 causes vibrational energy to begin to build up 30 in the wheels traversing the running rails. However, before the amplitude of the vibrational forces is sufficient to cause wheel squealing noises, the flanges of the wheels will contact the tread of the rubber tires 32. The rubber tires provide an energy dampening or absorbing effect on the passing wheels so that the vibrational forces are removed and dissipated by the mechanism friction and viscosity of the elastomer tire and wheel assembly. Thus, energy is removed from the wheels of 35 the passing cars by the first set of vibration absorbing wheel and tire assemblies of the car retarder 1. It will be appreciated that the engagement of the car wheel flanges with the tire causes the contacted wheel and tire assemblies to rotate so that the amount of abrasive frictional wear is minimized. It will be noted that the diameter of the wheel and tire assemblies will determine the length of arcuate contact between the flanges and the rubber tire and, in turn, the angular rotation of the rubber tires. Thus, the vibration dampening or absorbing effect continues through the arcuate contact of the flanges with the rubber tires. As the vehicle wheels W disengage the rubber tires 32, vibrational energy is again imparted to the wheels W due to their sole engagement with the running rails and the closed brake shoes 12 and 13. It will be appreciated that the distance 40 between the first pair of wheel and tire assemblies 30 and the second pair of wheel and tire assemblies 30 is chosen to be less than that required to have the vibra-

tional force built up to the point where wheel squealing will occur. Thus, the vehicle wheels will contact the periphery of the rubber tires of the second pair of wheel and tire assemblies before any wheel screeching noises occur so that the impressed vibrational forces are again absorbed and dissipated by the dampening action of a second pair of vibration absorbing rotary devices. Similarly, when the passing wheels disengage the second wheel and tire assemblies 30, vibrational energy is again imparted to the wheels W but the wheels will engage the third pair of wheel and tire assemblies 30 before the build up is capable of causing the production of wheel squealing noises. The energy build up and vibrational dampening is repeated as the wheels pass from the third pair of wheel and tire assemblies to the fourth pair of wheel and tire assemblies, etc. until the wheels emerge from the car retarder and exit onto the stack rails 26 and 27. That is, the vibrational forces assimilated by the vehicle wheels are repeatedly damped and dissipated by the series of vibrational absorbing wheel and tire assemblies 30 located along the length of the car retarder 1 so that wheel screeching sounds are prevented from being produced by the slip-slide action which takes place between the sides of the car wheels W and the surfaces of the brake shoes 12 and 13. Accordingly, the plurality of vibrational absorbing rotary devices 30 efficiently and effectively prevents the production of irritating and injurious wheel squealing noises which would normally be generated by car retarders in railroad classification yards.

It will be appreciated that various changes, alterations and modifications may be made in the embodiment of the presently described arrangement without departing from the spirit and scope of the subject invention. For example, the size of the wheel and tire may be increased or decreased to vary the contact time between the flanges of the vehicle wheel and the tire 30 to remove a more or a less amount of vibrational energy from the vehicle wheels. Similarly, the distance between the adjacent pair of the wheel and tire assemblies may be changed if a lesser amount of noncontact time is required to prevent wheel squealing noises or if a greater amount of contact time is necessary to stop the occurrence of wheel screeching sounds. It is understood that the rubber tire 32 may be replaced by other suitable elastic material or vibrational dampening material such as, plastic and the like. In addition, the wheel and tire assemblies may obviously be arranged in staggered relationship, and the number of wheel and tire assemblies per retarder may be varied in accordance with the particular need of each specific installation. It is also understood that the wheel and tire assemblies may be used on curved track sections or where a tight gauge occurs in the trackway to reduce the production of wheel squealing noises. Therefore, it is intended that the subject matter contained in the forego-

ing description and shown in the accompanying drawings should be interpreted as illustrative and not in a limiting sense.

Having now described the invention what we claim as new and desire to secure by Letters Patent, is:

1. In combination, a railroad car retarder having a plurality of operating units disposed along the length of a running rail of a trackway, an elongated braking bar disposed on each side of said running rail and carried by said plurality of said operating units, said elongated braking bar including a brake beam and a brake shoe for engaging the wheels of railway vehicles, characterized by a plurality of vibration absorbing rotary devices disposed at selected points along the running rail for contacting the vehicle wheels for removing vibrational energy from the wheels for preventing the production of wheel screeching sounds.
2. The combination, as defined in claim 1, wherein said vibration absorbing rotary devices contact the flange of the vehicle wheels.
3. The combination, as defined in claim 1, wherein said vibration absorbing rotary devices are elastic tires.
4. The combination, as defined in claim 1, wherein each said vibration absorbing rotary device includes a support shaft which is secured to the running rail.
5. The combination, as defined in claim 1, wherein each of said vibration absorbing rotary devices includes a rubber tire bolted to the web portion of the running rail.
6. The combination, as defined in claim 5, wherein said rubber tire is vertically adjustable for compensating for mechanical wear.
7. The combination, as defined in claim 1, wherein said vibration absorbing rotary devices include a pneumatic tire.
8. The combination, as defined in claim 1, wherein said vibration absorbing rotary device includes a semipneumatic tire.
9. The combination, as defined in claim 1, wherein said vibration absorbing rotary devices include a solid rubber tire.
10. The combination, as defined in claim 1, wherein each of said vibration absorbing rotary devices includes a wheel and tire assembly which is adjustably rotatably supported relative to the running rail by a wheel and axle member.
11. In combination, a section of railway trackway for guiding and supporting the wheels of passing railway vehicles characterized by a plurality of vibrational energy absorbing rotary devices disposed at selected points along the section of railway trackway and securely fastened to the trackway for contacting the vehicle wheels for removing vibrational energy from the wheels for preventing the production of wheel squealing noises.
